(57) **CLAIM**

The ornamental design for a tubular support for golf clubs, as shown and described.

DESCRIPTION

FIG. 1 is an overhead perspective view of the present invention in a working state.

FIG. 2 is a rear view of the present invention.

FIG. 3 is a front view of the present invention.

FIG. 4 is a side view of the present invention.

FIG. 5 is a side view of the present invention.

FIG. 6 is an overhead view of the present invention; and,

FIG. 7 is an underside view of the present invention.

The broken lines showing golf clubs are for the purposes of illustrating environment and form no part of the claimed design.
